US00D681476S

(12) **United States Design Patent**
Broen et al.

(10) **Patent No.:** **US D681,476 S**
(45) **Date of Patent:** **** May 7, 2013**

(54) **COMBINED CONTAINER AND OVERCAP**

(75) Inventors: **Nancy L. Broen**, Racine, WI (US);
Brook S. Kennedy, Glen Ridge, NJ (US); **Hideaki Matsui**, New York, NY (US); **Matthew N. Thurin**, Wauwatosa, WI (US); **Richard A Whitehall**, New York, NY (US)

(73) Assignee: **S.C. Johnson & Son, Inc.**, Racine, WI (US)

(**) Term: **14 Years**

(21) Appl. No.: **29/385,191**

(22) Filed: **Feb. 10, 2011**

(30) **Foreign Application Priority Data**

Aug. 12, 2010 (EM) 001229678

(51) **LOC (9) Cl.** **09-01**

(52) **U.S. Cl.**

USPC **D9/689**

(58) **Field of Classification Search** D9/600-681, D9/682-694, 763, 764, 767, 772-781, 500-505, D9/516, 526, 529, 530, 537-546, 549-575, D9/434-454; 222/129, 135, 153.01, 153.03, 222/153.04, 153.09, 153.11-153.14, 182, 222/631, 635, 209, 211-213, 215, 321.7-321.9, 222/372, 373, 378, 379, 383.1, 384-386, 222/398, 400.7, 400.8, 401, 402.1-402.25

See application file for complete search history.

Primary Examiner — Catherine Tuttle

(57) **CLAIM**

The ornamental design for a combined container and overcap, as shown and described.

DESCRIPTION

FIG. 1 is a top, front and right isometric view of the combined container and overcap showing our new design; FIG. 2 is a front elevational view of FIG. 1; FIG. 3 is a rear elevational view of FIG. 1; FIG. 4 is a right side elevational view of FIG. 1; FIG. 5 is a left side elevational view of FIG. 1; FIG. 6 is a top plan view of FIG. 1; FIG. 7 is a bottom plan view of FIG. 1; FIG. 8 is a top, front and right isometric view of the combined container and overcap showing a modified embodiment of our new design; FIG. 9 is a front elevational view of FIG. 8; FIG. 10 is a rear elevational view of FIG. 8; FIG. 11 is a right side elevational view of FIG. 8; FIG. 12 is a left side elevational view of FIG. 8; FIG. 13 is a top plan view of FIG. 8; and, FIG. 14 is a bottom plan view of FIG. 8.

The broken lines are included for the purpose of illustrating portions of the combined container and cap that form no part of the claimed design.

1 Claim, 8 Drawing Sheets
